UNITED STATES PATENT OFFICE

149,944

DESIGN FOR A PICTURE FRAME

Wilson K. Huffman, Baltimore, Md.

Application May 7, 1947, Serial No. 138,862

Term of patent 3½ years

(Cl. D29—20)

To all whom it may concern:

Be it known that I, Wilson K. Huffman, a citizen of the United States, residing in the city of Baltimore and State of Maryland, have invented a new, original, and ornamental Design for Picture Frame, of which the following is a specification, reference being had to the accompanying drawing, forming part thereof, and wherein:

The essential features of my design reside in the portion shown in full lines.

I claim:

The ornamental design for a picture frame, as shown and described.

WILSON K. HUFFMAN.
